(57) **CLAIM**

The ornamental design for a computer, as shown and described.

DESCRIPTION

FIG. 1 is a perspective view of a computer in accordance with the new design;

FIG. 2 is a front view of the computer of FIG. 1;

FIG. 3 is a back side view of the computer of FIG. 1;

FIG. 4 is a left side view of the computer of FIG. 1;

FIG. 5 is a right side view of the computer of FIG. 1;

FIG. 6 is a top plan view of the computer of FIG. 1;

FIG. 7 is a bottom plan view of the computer of FIG. 1; and,

FIG. 8 is another perspective view of the computer of FIG. 1.

The broken lines in the drawings are directed to portions of the depicted computer that form no part of the claimed design.

1 Claim, 7 Drawing Sheets
